UNITED STATES PATENT OFFICE

159,718

TOY BALLOON OR SIMILAR ARTICLE

Frederick K. Daniel, Kew Gardens, and Edward
N. Horn, New York, N. Y.

Application October 4, 1947, Serial No. 141,752

Term of patent 7 years

(Cl. D34—15)

To all whom it may concern:

Be it known that we, Frederick K. Daniel and Edward N. Horn, both citizens of the United States, and residents respectively of Kew Gardens, county of Queens, and State of New York, and New York city, county and State of New York, have invented a new, original, and ornamental Design for Toy Balloon or Similar Article, of which the following is a specification, reference being had to the accompanying drawings, forming part hereof and in which

The single figure is a side perspective view of a toy balloon or similar article, showing our new design.

We claim:

The ornamental design for a toy balloon or similar article, substantially as shown.

FREDERICK K. DANIEL
EDWARD N. HORN.
